GARTER PURSE

Emerson C. Bronson, Omro, Wis.

Application March 14, 1940, Serial No. 323,859

1 Claim. (Cl. 224—26)

The present invention relates to purses and more particularly to garter purses; and to a method of making the same.

An object of the invention is to provide an improved garter purse which can be readily applied to the leg of a wearer, and which will be securely held in place without discomfort and without being conspicuous.

Another object of the invention is to provide a garter purse which will reliably hold the contents although permitting convenient access thereto, and which is of simple and inexpensive construction.

A further object is to provide an improved method of making the purse which will permit rapid and economical manufacture.

The invention further consists in the several features hereinafter described and claimed.

This application constitutes a continuation in part of my copending application Serial No. 20 202,649, filed April 18, 1938.

In the accompanying drawings, illustrating certain embodiments of the invention,

Fig. 1 is a front view of one form of purse constructed in accordance with the invention, as it appears in use on a wearer's leg;

Fig. 2 is a front perspective view of the purse;

Fig. 3 is a rear perspective view of the purse;

Fig. 4 is a sectional elevation taken generally along the line 4—4 of Fig. 2;

Fig. 5 is a sectional elevation taken generally along the line 5—5 of Fig. 2;

Fig. 6 is a front perspective view of the purse with a sheath thereof removed;

Fig. 7 is a fragmentary top view of the purse, parts being broken away and parts being shown in section;

Fig. 8 is another fragmentary top view of the purse, a portion of a leg band thereof being shown by dotted lines in a looped adjusting position;

Fig. 9 is a vertical sectional view taken generally along the line 9—9 of Fig. 1;

Fig. 10 is an inner view of the sheath before application to the purse;

Fig. 11 is a plan view of the purse as it appears in an intermediate stage of manufacture;

Fig. 12 is a sectional view taken generally along the line 12—12 of Fig. 11, the purse parts resting on a support;

Fig. 13 is a view similar to Fig. 2, but showing a modified form of garter purse;

Fig. 14 is a fragmentary top view of the purse of Fig. 13, parts being omitted and broken away and parts being shown in section;

Fig. 15 is a front perspective view of the purse of Fig. 13 with the sheath thereof removed, and

Fig. 16 is a sectional elevation taken generally along the line 16—16 of Fig. 13.

The garter purse of this invention is intended

to be worn by women, and when in use encircles the leg of the wearer, as indicated in Fig. 1 of the drawings. The purse is located well above the knee and adjacent to the upper edge of a stocking 20 which encases the leg and which is held up by one or more of the usual hose supporters 21 attached to a corset or girdle 22, each supporter having the usual clasp 23 for engaging the upper edge portion of the stocking.

10 In the form of garter purse shown in Figs. 1 to 12, 24 designates a receptacle or pocket adapted to hold money and other articles. The pocket comprises two identical blanks or pieces of flexible material, 25 and 26, such as chamois or other soft leather, secured together along their lower and opposite side edges by a line of stitching 27, the pocket being open along its top. The blanks 25 and 26, which are of generally rectangular shape, form the outer and inner wall members of the pocket. The open top of the pocket is provided with a closure in the form of a slide fastener comprising complementary strips or tapes 28 and 29 which are secured to the inner faces of the upper edges of the wall members 25 and 26 by respective lines of stitching 30 and 31 and which carry along their longitudinal free edges interengaging gripping fingers 32 releasably joined by a slidable actuator 33 of any well known construction.

30 The upper edge of the inner wall member 26 of the pocket is attached by the line of stitching 31 to a leg-encircling band 34 of elastic material, preferably an elastic fabric, the pocket being suspended by the band. The band is here shown to extend along the inner face of the pocket wall member 26. The short end of the band 34 is looped or doubled on itself at 35 and passed through a link or connecting buckle 36, the extremity of this doubled end of the band lapping the pocket and being interposed between the pocket wall members and secured by the stitching 27, as seen in Fig. 7. The long end of the band passes through a take-up buckle 37 and has a looped or doubled terminal portion which 40 passes through the link 36, the extremity of the looped portion being secured to the middle bar of the take-up buckle.

The garter purse is provided with shielding means comprising a sheath, designated generally by 38, formed by outer and inner ribbons 39 and 40, respectively, secured together by longitudinal lines of stitching 41, the inner ribbon being here indicated as narrow and shorter than the outer ribbon. These sheath-forming ribbons are preferably Shirred or gathered to accommodate stretching of the elastic band enclosed between them. The ends of the inner ribbon, 40, are adjacent to the opposite side edges of the pocket, as seen in Fig. 3, thus leaving openings through 55 which the elastic band may be temporarily with-

drawn in looped formation, as indicated by dotted lines in Fig. 8, to facilitate adjustment of the band. The end portions of the outer ribbon extend over the outer wall member 25 of the pocket and are secured together by stitching 42, Fig. 2. The upper portion of the outer ribbon is tacked by stitching 43 to the outer wall of the pocket, and an ornamental bow 44 is secured to the joined ends of the outer ribbon. The upper edge of the outer ribbon preferably extends higher than the pocket closure 32, 33, so as to shield the closure and to avoid accidental opening.

In use, the purse encircles the wearer's leg well above the knee and is wholly or partially covered by the upper edge of the stocking 20. The garter clasp 23, which engages the upper edge of the stocking, also embraces the leg band, as seen in Fig. 9, so as to securely hold the purse in place. Preferably, the clasp embraces the doubled short end of the leg band adjacent to a side edge of the pocket, so as to resist any tendency to crumple or fold the band. The pocket 24 is placed at the side of the garter toward the inner side of the leg, as seen in Fig. 1, so as not to be noticeable through the garments. However, the pocket is sufficiently near the front of the leg to avoid interference with walking and to permit convenient access to the pocket. The fastener actuator 33, when in closed position, is preferably at the end of the fastener near the garter clasp. The flexible fastener, which extends longitudinally of the leg band, readily conforms to the variable curvature of this band. Since the purse is held up principally by the hose supporter 21, the leg band 34 need be under but slight tension, thereby avoiding discomfort and interference with the circulation of the blood. As the elastic leg band is secured to the inner wall member of the pocket there is no interference with the opening of the pocket by the slide actuator 33.

In some instances, the sheath may be omitted from the purse, as indicated in Fig. 6. Although the functions and advantages of the sheath are then absent, the purse still possesses utility and can be manufactured and sold at a lower cost.

The construction of the purse is such as to permit the use of a relatively simple and quick method of fabrication, illustrated in part in Figs. 11 and 12. The two pocket blanks 25 and 26 are laid inner face up on a sewing machine table 45. With the fastener tapes 28 and 29 connected by their gripping members 32, the tape 28 is laid over the proper edge of the pocket blank 25 and is secured thereto by the line of stitching 30. The other tape, 29, is then laid over the proper edge of the pocket blank 26, and the elastic band 34, the long end of which carries the buckle 37 and link 36, is laid over the tape 29, whereupon both the band and the tape are secured to the pocket blank 26 by the line of stitching 31. The short end of the elastic band is threaded through the link and doubled on itself, whereupon the pocket blanks are brought together into registering superposed relation and marginally secured together by the line of stitching 27, this stitching also securing in place the folded short end of the elastic band.

When the sheath 38 is to be provided, this member is slipped over the long end of the elastic band after the band is stitched to the pocket blank 26. After the pocket blanks are marginally stitched the ends of the outer sheath ribbon 39 are secured together by the stitching 42 and are secured to the outer wall member 25 of the pocket

by the tacking 43. The ornamental bow 44 is then applied to the outer ribbon.

The modified form of garter purse shown in Figs. 13 to 16 includes a receptacle or pocket 124 comprising a rectangular blank or piece of flexible material, such as chamois or other soft leather, folded on itself to constitute outer and inner wall portions 125 and 126, and sewn along opposite side edges by stitching 121, the pocket being open along its top. The open top of the pocket is provided with a slide fastener comprising parts 28 to 33 as in the device of Figs. 1 to 8.

The upper edge of the inner wall portion 126 of the pocket is sewn to the outer face of a leg-encircling band 134 of elastic material, the band being provided with a link 136 and take-up buckle 137, as in the device of Figs. 1 to 8.

The elastic band 134 is enclosed by a sheath 138 somewhat similar to the sheath 38 and formed by outer and inner fabric bands or ribbons 139 and 140, respectively, constituting shielding members, the inner ribbon being narrower than the outer ribbon. These ribbons, which are 20 Shirred or gathered to accommodate stretching of the elastic band, are connected by discontinuous seams 141 for most of their length. If desired, one or both of the ribbons may be tacked at intervals to the elastic band, as indicated at 25 141'. In the region of the pocket 124 the ribbons are not attached to each other, but the inner ribbon 140 is secured along the elastic band by lines of stitching 131, Fig. 16, which also secure the pocket to the elastic band, and the outer 30 ribbon 139 is secured to the outer wall of the pocket by a line of stitching 143, Fig. 13. A part 35 138' of the sheath, Fig. 13, is slidable on the elastic band near the pocket so that the sheath may be temporarily pushed back for access to the adjusting members 136 and 137.

The garter purse of Figs. 13 to 16 is used in the same manner as the purse of Figs. 1 to 12, as indicated in Fig. 1. The fastener and its slide- 45 able actuator, as well as the band-adjusting members, are normally shielded by the sheath 138, so that the shielded parts will not come into contact with the skin or the garments and the fastener will be protected from accidental opening.

50 Although the sheath possesses certain advantages, it may in some instances be omitted from the purse, as indicated in Fig. 15, with a corresponding reduction in the cost of the purse.

What I claim as new and desire to secure by 55 Letters Patent is:

A garter purse adapted to be placed within the upper edge portion of a wearer's stocking comprising a pocket having an opening extending along its top portion and having a slide fastener 60 for said opening including a slideable actuator, an elastic leg band secured to the inner wall of said pocket, said pocket and its fastener being relatively pliable to conform to the leg curvature, and outer and inner flexible, pliable, shielding ribbons for said leg band connected to form a tubular sheath for said band, said outer and inner ribbons extending along the respective outer and inner sides of said pocket to form shields for said pocket and its fastener and having free upper 65 edges extending above said pocket, and said ribbons being disconnected from each other where they extend along said pocket to permit free access to said slide actuator and pocket opening.
